ULTRA HIGH VACUUM PUMP FOR LABORATORIES OR THE LIKE

Allen R. Hamilton, Rochester, and Carl G. Thoresen, Hilton, N.Y., assignors to Consolidated Vacuum Corporation, Rochester, N.Y., a corporation of New York

Filed Dec. 14, 1960, Ser. No. 63,223

Term of patent 14 years

(Cl. D65—1)

FIG. 1

FIG. 2

FIGURE 1 is a perspective view of an ultra high vacuum pump for laboratories or the like embodying our new design; and

FIGURE 2 is a bottom plan view thereof.

The sides not shown are substantially the same in appearance as the sides shown.

We claim:

The ornamental design for an ultra high vacuum pump for laboratories or the like as shown and described.
